Primary Examiner — Robert M. Spear

(57) CLAIM

The ornamental design for a case for spoon or fork, as shown and described.

DESCRIPTION

1. Case for spoon or fork

1.1 : Perspective

1.2 : Front

1.3 : Back

1.4 : Top

1.5 : Bottom

1.6 : Left

1.7 : Right

The combination of the shape and shape of a case for spoon or fork is the key point of the design; the case is divided into the upper and bottom parts and can contain a spoon or a fork inside.
